UNITED STATES PATENT OFFICE.

JOHN H. MANSUR, OF ROYERSFORD, PENNSYLVANIA, ASSIGNOR TO THE
KEYSTONE METER COMPANY, OF PENNSYLVANIA.

DESIGN FOR A FRAME FOR GAS-METER PROVERS.

SPECIFICATION forming part of Design No. 27,611, dated August 31, 1897.

Application filed July 14, 1897. Serial No. 644,579. Term of patent 7 years.

To all whom it may concern:

Be it known that I, JOHN H. MANSUR, a citizen of the United States, residing at Royersford, in the county of Montgomery, State of Pennsylvania, have invented and produced a new and original Design for the Frame of a Gas-Meter Prover, of which the following is a specification, reference being had to the accompanying drawings, forming part thereof.

10 The leading feature of my design for the frame of a gas-meter prover is a frame consisting of standards, a base from which said standards rise, eyes through which they pass, and a spider at the tops of said standards.

15 Figure 1 represents a perspective view of a portion of a gas-prover embodying my design. Fig. 2 represents a top or plan view thereof.

A designates the base of a prover for a gas-meter, and B designates standards which rise from said base.

C designates eyes on the side of the prover, the same having the standards pass through them.

D designates a spider consisting of the annulus E and arms F, which radiate therefrom. 25 The tops of the standards join said arms.

What I claim is—

The design for the frame of a gas-meter prover substantially as described and shown.

JOHN H. MANSUR.
